US0D1011968S

(12) **United States Design Patent** (10) **Patent No.:** **US D1,011,968 S**
(45) **Date of Patent:** **** Jan. 23, 2024**

(54) **BICYCLE**

(71) Applicant: **SHENZHEN ZHELUN TECH CO., LTD.**, Shenzhen (CN)

(72) Inventors: **Feng Tan**, Shenzhen (CN); **Bo Zhang**, Shenzhen (CN); **Guanghui Hou**, Shenzhen (CN); **Donghao Li**, Shenzhen (CN)

(73) Assignee: **SHENZHEN ZHELUN TECH CO., LTD.**, Shenzhen (CN)

(**) Term: **15 Years**

(21) Appl. No.: **29/827,331**

(22) Filed: **Feb. 18, 2022**

(30) **Foreign Application Priority Data**

Aug. 23, 2021 (CN) 202130550135.6

(51) **LOC (14) Cl.** **12-11**

(52) **U.S. Cl.**

USPC **D12/111**
